ATTORNEY

UNITED STATES PATENT OFFICE.

EMMET P. GRAY, OF DETROIT, MICHIGAN.

MUFFLER.

Application filed August 30, 1920. Serial No. 406,918.

To all whom it may concern:

Be it known that I, EMMET P. GRAY, a citizen of the United States, and residing at Detroit, in the county of Wayne and State of Michigan, have invented a new and Improved Muffler, of which the following is a specification.

This invention relates to means for reducing the sounds of the exhaust of internal combustion engines, and its object is to provide a muffler which shall have minimum diameter, which shall produce a minimum of back pressure, and which may be produced at low cost.

15 A feature of this invention consists in the provision of two or more sheet metal tubes one within the other, the tubes having longitudinal flanges nested together, the arrangement providing a silencing device 20 within the outer tube or shell and providing for an inflow of exhaust gases at one end to the silencing device and discharging to atmosphere from the structure at the opposite end. Further, the arrangement of 25 the tubes for the flow of gases is such that the gases from chamber to chamber of the several tubes expanding as the exhaust gases progress toward the exhaust end and resulting in a merging of the successive puffs 30 of the gas received by the muffler so that the discharge is practically continuous and not intermittent as with previously known types of mufflers.

This invention further consists in closing 35 the rear end of the intermediate tube onto the inner tube, in closing the rear end of the outer tube onto the intermediate tube, in forming the intermediate tube with a series of holes and in closing its front end.

40 It also consists in the details of construction illustrated in the accompanying drawing and particularly pointed out in the claims.

In the accompanying drawing, Fig. 1 is 45 a longitudinal section of this improved muffler. Figs. 2 and 3 are sections on the lines 2-2 and 3-3 of Fig. 1 respectively.

Similar reference characters refer to like 50 parts throughout the several views.

The demand for low slung motor car bodies carries with it a demand for mufflers of smaller diameter than those now usually provided. Furthermore, the cast iron heads now usually employed are very heavy so 55 that the weight of the mufflers is objectionable. The purpose of the usual muffler for

an internal combustion engine is to receive the exhaust gases discharged by successive exhaust impulses of the engine and to reduce the pressure and therefore the explosive force of the successive puffs whereby the same may be materially less noisy without production of material back pressure. 60 My improved muffler seeks to still further reduce the noise of the exhaust gases and 65 produce a continuous flow thereof at the discharge end is practically constant, and it is to be understood further that the device may be made in various forms and with two or more tubes. The particular form 70 here shown is only one exemplification of the invention.

In the present case I have provided three tubes 1, 2 and 3, one within the other, all of substantially the same length, the front 75 ends of the tube 2 being closed and at some distance back of the front end of the tube 1, while the front end of the tube 3 is open and at about the same distance back of the front end of the tube 2. The several tubes are 80 preferably formed with longitudinal flanges 4, 5 and 6 which are nested and secured together with rivets 7.

The exhaust pipe 8 of the engine is preferably formed with a collar 9 and the front 85 end of the tube 1 is gripped onto this collar by means of a bolt 10 although any other desired means may be employed to form this connection. The rear end of the tube 3 is similarly gripped onto a tail pipe 90 12. The rear end of the tube 3 is gripped by the pinched down end of the tube 2, rivets 13 being inserted to secure the tubes together, while rivets 14 similarly secure the tube 1 onto the tube 2. The tube 2 is 95 formed with any desired number of perforations 15.

The cross sectional area between the tubes 1 and 2 should be as large and preferably one-fourth larger than the area of the passage of the exhaust pipe. I prefer to have the net area of the tube 1 somewhat larger than the net area of the tube 2 and that somewhat larger than the net area of the tube 3, twenty per cent being sufficient in 105 each case. I prefer to make the length of the tube 1 from ten to fifteen times its diameter, which differs greatly from the present types of mufflers whose lengths are usually less than three times the diameters. 110

When a puff of exhaust gases enters this muffler, a portion immediately passes

through the front holes 15 into the intermediate tube 2 and then passes into the inner tube 3. As the gases move along in the tube 1, other portions pass through the 5 succeeding holes 15 and then forward in the tube 2 to the front end of the tube 3 and then rearwardly therein. As a result, by the time the gases have reached the rear end of the tube 1 their pressure has been 10 greatly reduced and a substantially constant stream of these gases has moved forward within the tube 2 to the front end of the tube 3 and rearward therein. The back pressure created by this muffler is only a 15 few ounces and the escape of the gases from the tail pipe 12 is uniform and almost noiseless, even when the muffler is used with high duty engines.

Any usual means may be employed to prevent 20 the radiation of heat from the muffler, but the layer of asbestos between two sheets of steel which are used to form outer shells of many mufflers in order to deaden the drumming noise of the puffs of the exhaust 25 when it enters the mufflers will ordinarily be found unnecessary, especially when there is sufficient space to build the present muffler of proper length. The holes 15 are preferably in two rows which are diametrically 30 opposite each other and equal distances from the flanges 5, and their combined area is somewhat greater than the net area of the pipe 1.

In order to prevent carbon from lodging 35 in the front end of the intermediate tube and between the tubes, I may make use of an ejector for causing a more rapid flow of 40 gases through the inner tube. To this end I mount a small pipe 16 in the closed front 45 end of the tube 2, the front end of the pipe 16 being preferably enlarged and the rear end reduced, which pipe is in the line of the exhaust pipe 8 and thus receives gases at their highest speed.

While I have shown the tubes to be cylindrical, I do not wish to be limited thereto as the form of these tubes and the other details of the muffler may all be changed by those skilled in the art without departing 50 from the spirit of my invention as set forth in the following claims.

Instead of having the flanges 4, 5 and 6 on the lower side of the muffler they may extend up or in any other direction and the 55 muffler may be inclined at any angle which may be found most desirable.

As previously stated, one of the main features of this invention is in the supporting of one tube within another by nesting 60 of the flanges and while an inner, outer and intermediate tube have been shown arranged to produce a practically continuous flow of gas from the discharge end at practically constant pressure, it is to be understood 65 that the invention as set forth in the ap-

pended claims may be embodied in a form and arrangement of the tubes other than is shown by the drawing.

I claim:

1. In a muffler, the combination of outer, 70 inner and intermediate tubes, the intermediate tube being within the outer and without the inner tube and being perforated and having a closed forward end, the opposite end of the intermediate tube being closed 75 around the inner tube a distance from the end thereof and the same end of the outer tube being closed around the intermediate tube a distance from the end thereof.

2. In a muffler, the combination of outer, 80 inner and intermediate tubes, the intermediate tube being within the outer and without the inner tube and being perforated and having a closed forward end, the opposite end of the intermediate tube being closed 85 around the inner tube and the same end of the outer tube being closed around the intermediate tube, the front open end of the inner tube being a distance from the front end of the outer tube and the front end of 90 the intermediate tube being between the front ends of the other two.

3. In a muffler, the combination of outer, 95 inner and intermediate tubes, the intermediate tube being within the outer and without the inner tube and being perforated and having a closed forward end, the opposite end of the intermediate tube being closed around the inner tube a distance from the end thereof and the same end of the outer 100 tube being closed around the intermediate tube a distance from the end thereof, said tubes being formed of strips of sheet metal, the central portions of which are in tubular form and the edges constituting parallel 105 flanges which are nested and secured together.

4. In a muffler, the combination of outer, 110 inner and intermediate tubes, the intermediate tube being within the outer and without the inner tube and being perforated and having a closed forward end, the opposite end of the intermediate tube being closed around the inner tube a distance from the end thereof and the same end of the outer 115 tube being closed around the intermediate tube a distance from the end thereof, said tubes being cylindrical and eccentric to each other, the holes in the intermediate tube being in two diametrically opposed rows. 120

5. In a muffler, the combination of outer, 125 inner and intermediate tubes, the intermediate tube being within the outer and without the inner tube and being perforated and having a closed forward end, the opposite end of the outer tube being closed to prevent the escape of gases therefrom, and an ejector tube mounted in the closed forward end of the intermediate tube and extending rearwardly to the inner tube to conduct 130

- gases from the front end of the outer tube directly into the front end of the inner tube.
6. In a muffler, the combination of inner and outer tubes formed of sheet metal, the central portions of which are tubular in form and each provided with a longitudinal flange, the flange of the inner tube being nested in and secured to the flange of the outer tube.
7. In a muffler, the combination of outer and inner members, the central portion of each member being curved and the edges of each member constituting parallel outwardly extending flanges, the flanges of the two members being nested and secured together.
8. A muffler comprising an interior silencing device having an outwardly extending rib, and a shell enclosing said silencing device and having longitudinal edges extending outwardly and fitting against and over the rib on the interior member.
9. A muffler and a pipe extending into one end thereof, said muffler having a shell formed of sheet metal which is bent around the pipe and having the two edges outwardly bent in parallel relation providing a flange and an external shell of sheet metal of greater diameter positioned thereabout and having similar flanges engaging the flange of the first named shell, the flanges of the two shells being secured together.
10. A muffler comprising a tubular metallic shell adapted to receive a pipe of less diameter in one end, said end being flattened in part to cause the metal to fit around the pipe.
11. In a muffler, the combination of an interior silencing device having an exterior longitudinal radial rib, and a shell connected with said silencing device and formed with a longitudinal radial rib embracing and fitting against the rib on the interior member.
12. A muffler comprising an exterior tubular shell formed to provide an external longitudinal flange, an inner tubular silencing member having an external longitudinal flange fitting and secured to the flange of the outer member, providing a closed seam, the parts being so arranged at one end to fit an exhaust pipe discharging into the silencing member and opening at the opposite end to atmosphere.
13. A muffler comprising an exterior shell formed of a sheet of metal, the edges being brought together and outturned providing a longitudinal flange, an inner silencing device provided with a flange secured to the flange of the outer shell, the devices being arranged to provide an inflow of exhaust gases at one end to the silencing device and to discharge from the outer member at the opposite end.
14. A muffler comprising an exterior shell formed of sheet metal folded in tubular form with the edges outwardly extending providing a longitudinal rib, a tubular silencing device within the outer member formed of sheet metal having an external flange extending between the outwardly extending rib parts of the outer member and secured therebetween, the arrangement providing for a flow of gases from one end to the other of the device.
15. A muffler comprising a series of shells of tubular form each formed of a sheet of metal and shaped to provide a longitudinal rib, the said shells being one within the other and apertured to provide communication successively one to the other, the ribs of the several shells being nested together and secured in position, and a pipe leading into the shell of least diameter at one end, the shell of larger diameter opening to atmosphere at the opposite end.
16. A muffler comprising an exterior tubular member of sheet metal having an outwardly extending longitudinal flange of two spaced parts, an inner silencing member also having a longitudinal flange nesting in and supporting between the flange parts of the outer member closing the same to atmosphere, the arrangement providing a device adapted for attachment to an exhaust pipe at one end and to discharge to atmosphere at the opposite end.
17. A muffler comprising an outer tubular shell, edge portions of which are outturned and spaced providing external longitudinal flanges, a tubular sheet metal silencing device therewithin also provided with a flange positioned between the flanges of the outer shell, the parts being arranged to receive exhaust gases at one end and discharge the same from the other end only of the structure, and means intermediate the ends causing the gases to pass successively from the interior of one member to the interior of the other.
18. A muffler comprising an exterior shell of sheet metal having longitudinal flanges at one side formed by the outwardly extending edges of the sheet forming the shell, an interior silencing device of tubular form extending longitudinally of and less in diameter than the exterior member and having a longitudinal flange nesting in and secured to the flanges of the exterior member, the inner member having a series of apertures therein, and means between the members whereby gases passing into the exterior member are passed into the interior member before discharge from the muffler, the structure being adapted for connection to an exhaust piping at one end and discharging to atmosphere at the opposite end only.
19. A muffler comprising an interior silencing device having an outwardly extending rib, and a shell enclosing said silenc-

ing device and having its longitudinal edges extending outwardly and fitting against and over the rib on the interior member.

20. A muffler comprising a tubular shell adapted to receive a pipe of less diameter in one end, said end being flattened in part to cause the metal to fit around the pipe.

21. In a muffler, the combination of an

interior silencing device having an exterior longitudinal radial rib, and a strip formed ¹⁰ into a tube to surround said silencing device and having an outwardly projecting longitudinal rib fitting over the rib on the interior member.

EMMET P. GRAY.
